CLAIM

The ornamental design for a two-button controller for a fleet management system, as shown and described.

DESCRIPTION

FIG. 1 is a perspective view of the two-button controller having a front cover taken from the top, right front thereof; FIG. 2 is a front elevational view thereof; FIG. 3 is a rear elevational view thereof; FIG. 4 is a left side elevational view thereof; FIG. 5 is a right side elevational view thereof; FIG. 6 is a top plan view thereof; FIG. 7 is a bottom plan view thereof; and, FIG. 8 is a perspective view of the two-button controller of FIG. 1 with the front cover removed. The broken line showings in the figures are for illustrative purposes only and form no part of the claimed design.
